UNITED STATES PATENT OFFICE.

WILSON L. CAMPBELL, OF CHICAGO, ILLINOIS, ASSIGNOR, BY MESNE ASSIGNMENTS,
TO FIRST TRUST AND SAVINGS BANK, TRUSTEE, OF CHICAGO, ILLINOIS.

AUTOMATIC TELEPHONE-TESTING SYSTEM.

1,109,960.

Specification of Letters Patent.

Patented Sept. 8, 1914.

Application filed April 1, 1907. Serial No. 365,650.

To all whom it may concern:

Be it known that I, WILSON L. CAMPBELL, a citizen of the United States of America and resident of Chicago, Cook county, Illinois, have invented a certain new and useful Improvement in Automatic Telephone-Testing Systems, of which the following is a specification.

My invention relates to telephone exchange systems in general, but more particularly to automatic or semi-automatic systems, and especially to systems in which connectors are employed for establishing the final connections directly with the called telephone line.

Generally stated, the object of my invention is the provision of improved means for enabling an attendant at the exchange to test the subscribers' telephone lines, regardless of whether the same are busy or idle.

Special objects of my invention are the provision of improved means whereby the attendant may employ an automatic connector for automatically establishing connection with a more or less distant telephone line, so that he may then test the said line in the desired manner; the provisions of an arrangements by which an attendant at the main or central station may, by using the connectors, test any of the telephone lines leading into said central station, or leading to the exchange; the provision of means by which an attendant at the exchange may employ a connector for establishing connection with the line of any subscriber, whether the line be idle or busy, and may then shunt or short-circuit the condensers of the said connector, so as to afford a conductively continuous circuit for testing purposes; and the provision of certain details and features of improvement and combinations tending to increase the general efficiency and serviceability of a testing system of this particular character.

In the accompanying drawings, Figure 1 shows diagrammatically my testing connector A with the proper circuit connections leading to the jacks C and C' which may be located at a wire-chief's desk. The plug D is connected with the cord circuit which leads to the keys e, e' and e''. Of these keys e and e' may be adapted to connect the various testing devices usually found in a wire-chief's desk to the line. To the key e''

is attached a calling device F, which in turn 55 is normally connected with an operator's set shown at H. The conductors of the plug D' lead to the key f which is adapted to place ground on either of said conductors. The connector A is of the general type disclosed in United States Patent No. 815,176, 60 granted March 13, 1906, to Keith, Erickson and Erickson. At B is shown a central source of current-supply having its positive terminal preferably grounded at G. At I 65 is shown a ringer generator, and at K is represented a busy-signaling machine. At L is shown a selector switch of the general type disclosed in United States Patent No. 815,321, granted March 13, 1906, to Keith, 70 Erickson and Erickson, allotted to the line #220 which leads to the substation E. Fig. 2 is a diagrammatic perspective view of my testing connector switch A.

The connector switch A is an improvement upon the connector switch disclosed in said connector patent, whereby the connector switch A may be used for testing purposes, as well as for establishing the final connection in the usual manner. The mechanical 75 details of the selector L and of the connector A, as is well known, are very much the same, although there is some material difference in the circuits. For instance, the connector switch shaft 2 (Fig. 2) carries 80 the line wipers 3 and 4 and the private wiper 5. The connector switch is controlled by the calling subscriber through the medium of the vertical and rotary line relays 6 and 7. The vertical line relay 6 directly 85 controls the vertical magnet 8 and also the rotary magnet 9.

The function of the vertical magnet 8 is to give the shaft and shaft wipers a vertical motion, and the rotary magnet 9 imparts to 90 the said shaft and wipers a rotary or circular motion. The rotary line relay 7 controls the private magnet 10, which latter, under certain conditions, controls in turn the vertical and rotary magnets 8 and 9, the release 95 magnet 11, and also the side switch wipers 12, 13, 14 and 15. The said side switch, like the usual side switch, has a normal or first position, a second position and a third position. The release magnet 11 is also controlled by the vertical and rotary line relays 100 6 and 7 conjointly. By the use of the condensers 16 and 17 the connector divides the 105

circuit through it into two sections. When the side switch wiper 15 is in the third position the vertical line relay 6 controls the ringer relay 18 by means of which the ringer 5 generates. It may be bridged across the line conductors of the called subscriber. Instead of the usual back-bridge release relays of the connector in the said patent, there are now provided the relays 19 and 20 which 10 have one terminal connected with the battery lead and the other terminal leading to the jack C' (Fig. 1). The relay 20 is adapted, upon energizing, to operate and shift the springs 21 and 22 out of engagement with the springs 23 and 24 and into engagement with the springs 25 and 26. By the disengagement of the springs 21 and 23, and 22 and 24, the conductors 27 and 28 are disconnected from the vertical and rotary relays 6 15 and 7; and when the springs 21 and 22 engage the springs 25 and 26, respectively, as stated, the conductors 27 and 28 are metallically connected with the shaft wipers 3 and 4, around the condensers 16 and 17 20 (which divide the circuit through the connector into parts) and the side switch wipers 12 and 13, thus making the said circuit through the connector continuous from the conductors 27 and 28 to the connector 25 shaft wipers 3 and 4. By this operation it will be seen that incidentally the condensers 16 and 17 are short-circuited when the side switch is in third position. The relay 19 is adapted, when it energizes, to operate the 30 springs 29 and 30, thereby disconnecting the private wiper 5 from the side switch wiper 14. This provision is made in order that the connector switch may call-in and not receive the busy-release on a line for which 35 there is a guarding potential. The said relays 19 and 20 are controlled only from the jack C'; for when the connector is used in the ordinary way there would never be any occasion for short-circuiting the condensers 40 16 and 17, or for preventing the release of the connector when a busy line is called. Furthermore, the connector is provided with a normal post arm 31 which, when the shaft 45 2 is raised, permits the spring 32 to engage 50 with the spring 33, whereby the busy-signaling machine K is connected with the side switch wiper contact point 34.

The selector switch L is well known; the switch-shaft (not shown) carries the vertical 55 and rotary wipers 35 and 36, respectively, and the private wiper 37. The side switch is well known and comprises the side switch wipers 38, 39, 40 and 41, which may be designated as the vertical, rotary and private side 60 switch wipers, and the rotary magnet wiper, respectively.

The side switch is under the control of the private magnet 42, and in its normal or first position the wipers 38, 39, 40 and 41 occupy 65 the contact points 43, 44, 45 and 46, respec-

tively. In the second position they rest on the contact points 47, 48, 49 and 50, respectively, and in the third position the contact points 51, 52, 53 and 54 are engaged by their respective wipers. Through the medium of the vertical line relay 55, and while the side switch is in first position, the subscriber controls the vertical magnet 56, which latter operates to raise the switch shaft and wipers 35, 36 and 37 vertically. 70

By means of the rotary line relay 57, and while the side switch is in the first position, the subscriber controls the private magnet 42, and, therefore, the side switch. While the side switch is in second position the rotary magnet 58, which operates the switch shaft and wipers 35, 36 and 37 in a rotary direction, is energized. The vertical and rotary line relays 55 and 57, acting 75 jointly, provide the means whereby the subscriber controls the release magnet 59 while the side switch is in the first or second position. If the side switch passes to third position, then, since the selector L is of the trunk-release type, the selector is controlled 80 through the next switch, with which a connection is then established through the private wiper 87, and by means of the back-release relay 60. The bridge-cut-off relay 61 is adapted to open the connection 85 between the line relays 55 and 57 and between said relays and battery B. This is desirable, because if the relays are not disconnected from each other and the battery, the ringing current for signaling the subscriber may 90 then operate either or both of the relays 55 and 56 and cause some interference with the switch. It is also desirable to remove the bridge formed through the said relays from 95 across the line, to give the voice-currents 100 as clear a path as possible. 105

The substation E in connection with which I have elected to illustrate my invention comprises a receiver 62, a switch-hook 63 for controlling the substation circuits, which controlling operations are accomplished through the medium of any suitable means, such as the cam-arms 64, 65 and 66. As the switch-hook is lowered the cam-arm 64 momentarily presses the release springs 67, 68 and 69 into engagement, whereby the substation line conductors may be grounded simultaneously. When the switch-hook is down the cam-arm 65 engages the spring 70, thereby bridging the 115 ringer 71 across the line. Furthermore, when the switch-hook is down the said cam 65 disengages the springs 72 and 73, thus breaking the local circuit which includes 120 in series the primary winding 74, transmitter 75 and local battery 76. 125

The substation ground circuit is normally broken between the ground springs 77 and 78 by the cam-arm 66; but when the said 130 springs are together ground is provided to

the ground post 79, and to the release spring 69, as is usually the case in telephones of this type. The said substation comprises the usual induction-coil 80 having the primary winding 74 and secondary winding 81. Being an automatic substation, it is provided with the usual vertical and rotary impulse springs 82 and 83. Said substation is, of course, provided with a dial (not shown) which is secured to the shaft 84, together with the locking dog 85. Furthermore, there is a locking cam 86 that locks the dog 85 while the receiver is on the switch-hook, to prevent a rotation of the dial.

For operating the impulse springs 82 and 83 the substation is provided with an impulse wheel 87 that is secured to the shaft 84, which impulse wheel carries on its periphery the so-called vertical impulse teeth 88 and one rotary impulse tooth 89. The said impulse teeth are so arranged that when the dial is drawn down the impulse springs 82 and 83 are not carried into contact with the ground post 79; but as the dial 25 returns, first the vertical teeth engage the vertical impulse spring 82, and after they have completed their work the rotary impulse tooth 89 operates the rotary impulse spring 83. In this operation the subscriber's 30 vertical line conductor 90 is first given a number of ground impulses; and then the rotary line conductor 91 is given one ground impulse. It will be seen that as long as the dial is out of normal position the construction is such that the dog 85 permits the 35 primary circuit springs 92 and 93 to separate, thus preventing the impulses that are delivered to either line conductor from passing to the other.

Means whereby the subscriber may signal the called subscriber comprises the push-button spring 94 which normally engages the contact point 95; but when the button is pressed the spring 94 engages the contact 45 point 96, whereby the vertical line conductor may be grounded.

The operation of my testing connector is as follows: Suppose that it is desired to establish connection with the line conductors 90 and 91 leading to the substation E. The attendant inserts the plug D into the jack C, thereby placing in engagement the tip 97, sleeve 98 and ring 99 of the plug D with the tip spring 100, sleeve spring 101 and jack ring 102 of the jack C.

The engagement of the rings 102 and 99 places a guarding potential on the private conductor 103 which protects the trunk conductors 27 and 28. The attendant then operates the key e^2 , placing in contact the springs 106 and 107, and 108 and 109, whereby the operator's set H, in series with the calling device F, is bridged across the conductors 104 and 105 which lead to the trunk conductors 27 and 28. To call the number

220, which, it is assumed, is the number of the substation E, the attendant operates the calling device for the last two digits (2 and 0) only; for the calling device is already in connection with the connector trunk conductors 27 and 28, and the effect of grounding the line for the last two digits operates the connector. It will be evident that if another subscriber at a substation similar to the substation E were to call the number 220, 75 he would have to operate a first-selector, and that would require one digit. The first-selector would place him in connection with the connector A, or some other connector of the same group, which connector requires, as 80 already stated, an operation corresponding to two digits to complete the desired connection. It is obvious, therefore, that since the calling device F is already in direct connection with the connector A, the first digit 85 must be omitted in making the connection with the substation #220. It will be understood, of course, that any subscriber, in trying to call the substation #220, operates his dial for said first digit 2 and grounds his 90 vertical line conductor (similar to the vertical line conductor 90 of the substation E) twice, and the rotary line conductor (similar to the rotary line conductor 91) once. The result is, as already known, that the vertical 95 line relay 55 is operated twice, and the shaft of the selector is raised two steps to the second level, after which operation the impulse that comes in over the rotary line starts the selector rotating automatically until an idle 100 trunk line is found, the conductors of which, such as the conductors 27, 28 and 103, lead to a connector A or some other connector. The operator omits the first digit and takes up the call from the second digit 2. For this 105 digit 2 the button 110 is pressed and the spring 111 is carried out of engagement with the contact point 112 and into engagement with the ground post 113. This results in grounding the conductor 104, whereby an 110 energizing circuit is closed through the vertical line relay 6. This circuit extends from ground G' through the ground post 113, spring 111, springs 106 and 107, through the tip 97 to the spring 100, conductor 104, 115 trunk conductor 27, springs 21 and 23, vertical line relay 6 to the battery lead 114, thence through battery B to ground G. Each time that the vertical line relay 6 is 120 energized the line relay springs 115 and 116 are pressed into contact, thereby closing an energizing circuit through the vertical magnet 8 which operates in the usual manner, one step at a time, to carry the shaft wipers 3, 4 and 5 two steps opposite the level in 125 which are located the normal terminals of the line #220.

The energizing circuit for the vertical magnet may be traced from ground G' through the springs 116 and 115, through the 130

private magnet springs 140 and 141, conductor 142 to the side switch wiper 15, contact point 143 to the vertical magnet 8, thence to the battery lead 114, and through battery B to ground G. When the button 117 is pressed the spring 118 disengages from the contact point 119 and makes contact with the ground post 113, thereby closing an energizing circuit through the rotary line relay 7, said circuit extending from ground G' through the ground post 113 and spring 119, springs 108 and 109, sleeve 98 to the sleeve spring 101, conductor 105, trunk conductor 28, springs 22 and 24, through the rotary line relay 7 to the battery lead 114, thence through battery B to ground G. The rotary line relay, upon operating, closes an energizing circuit through the private magnet 10 which operates to release the connector side switch from first to second position.

The energizing circuit for the private magnet may be traced as follows: From ground G⁵ through the springs 116 and 144 to the private magnet 10, thence to the battery lead 114, and through battery B to ground G. The last digit being naught, the calling device is operated, as previously described, grounding the vertical conductor 27 ten times and the rotary line conductor 28 once. The vertical and rotary line relays 6 and 7 are operated over previously traced circuits. However, when the line relay springs 115 and 116 engage, a circuit is then closed through the rotary magnet 9, instead of through the vertical magnet 8, as follows: From ground G⁵ through the springs 116 and 115, as above, and through the private magnet springs 140 and 141 to the side switch wiper 15, thence through the contact point 145 to the rotary magnet 9, thence to the battery lead 114, and through battery B to ground G. Each time that the rotary magnet is energized it operates to rotate the shaft 2 and shaft wipers 3, 4 and 5, one step at a time, until the said wipers are carried into engagement with the normal conductors 120, 121 and 122, the former two of which lead to the line terminals of the desired subscriber.

50 The energizing of the rotary line relay 7, as previously stated, completes an energizing circuit through the private magnet 10 which now operates to release the side switch from second to third position, thus placing the side switch wipers 12, 13, 14 and 15 in contact with their respective contact points 123, 124, 125 and 126. Furthermore, when the side switch wiper 14 engages the contact point 125 a guarding potential 55 is established for protecting the called line. This potential extends from ground G² to the contact point 125, side switch wiper 14, through the springs 29 and 30 to the private wiper 5 which engages the private contact of the called line. Also the passage of the

side switch wiper 14 to third position closes an energizing circuit through the bridge-cut-off relay 61 of the selector L. This circuit extends from the side switch ground G² to the private wiper 5, over the guarding potential circuit already traced to the private normal conductor 122, through the switch shaft springs 146 and 147 of the first-selector L to the bridge-cut-off relay 61, thence to the battery lead 114 and through battery B to ground G. The line conductors 90 and 91 of the substation #220 are now extended to the jack C. The attendant may now insert the plug D' into the jack C', after restoring the key e², and establish connection with the relays 19 and 20.

By means of the key f an energizing circuit is then established through the relay 20, said circuit extending from ground G³ through the springs 127 and 128, through the sleeve 129 to the sleeve spring 130, conductor 131, through the relay 20 to the battery lead 114, thence through battery B to ground G. The said relay, upon energizing, operates to shift the springs 21 and 22 from the springs 23 and 24 to the springs 25 and 26. The engagement of the said spring closes a short-circuit or shunt around the condensers 16 and 17. The attendant may then operate the test keys e, e', etc., to perform any desired test on the line conductors with which the connector shaft wipers 3 and 4 are in connection. Should the attendant desire to signal the subscriber at substation #220 the key f is first restored to normal position, thus breaking the energizing circuit through the relay 20, which in turn removes the shunt from around the condensers 16 and 17, and the key e² is again operated; then the button 110 is pressed, whereby the spring 111 is pressed into engagement with the ground spring 113, whereby an energizing circuit is established through the connector vertical line relay 6, 105 as before. The said relay now operates to close an energizing circuit through the ringer relay 18, which operates in the usual manner to bridge the ringer generator I across the line conductors 90 and 91 to operate the ringer 71 at substation E.

The energizing circuit through the ringer relay 18 extends from ground G⁵ through the springs 116 and 115, and through the private springs 140 and 141 to the side switch wiper 15, thence to the contact point 126, through the ringer relay 18 to the battery lead 114, and through battery B to ground G. When the ringer relay 18 energizes, the springs 148 and 149 are disconnected from the line conductors 27 and 28, on the calling side, by leaving the springs 150 and 151, respectively, and are carried into engagement with the springs 152 and 153 that constitute the terminals of the

ringer generator I. The ringing current then passes out from the generator I through the said last-named springs, and through the side switch wipers 12 and 13 to the line 5 wipers 3 and 4, thence to the normal line conductors 120 and 121 and to the line conductors 90 and 91, and through the ringer 71, while the switchhook 63 is down. The subscriber at substation E, upon removing 10 the receiver 62 from the switchhook 63, may converse with the attendant over the circuit shown by the heavy lines. The release of the connector by the operator at H may be brought about when the springs 111 and 15 118 are pressed onto the ground post 113 simultaneously if the key e^2 is thrown, thereby grounding both conductors 27 and 28 simultaneously, which closes an energizing circuit through both vertical and rotary 20 relays 6 and 7 simultaneously, which operate to place the springs 132 and 133 in contact. An energizing circuit is thereby established through the release magnet 11, said circuit extending from ground G^4 25 through the ring 99 of the plug D to the ring 102 of the jack C, conductors 134 and 103, trunk-release springs 132 and 133, release magnet 11 to the battery lead 114, thence through battery B and to ground G. 30 The release magnet 11, upon energizing, operates to release the connector switch and restore the shaft wipers 3, 4 and 5 to normal position by attracting the armature 154, which then strikes the double dog 155 to the 35 right of the pivots 156, so as to remove the said double dog from engagement with the shaft 2, and so as to, at the same time, drive the side switch back to its normal position through the medium of the side switch link 40 157 that connects the double dog with the side switch. Of course, as soon as the shaft is deprived of the support provided by the double dog it is restored to normal position by the coiled spring which is provided for 45 that purpose and which is indicated at the top of the shaft.

Ordinarily, if any connector is operated to call a line that is busy, and the private wiper 5 is, therefore, rotated into engagement with a busy line, then when the last 50 rotary impulse comes in and the private magnet is energized and carries the private springs 158 and 159 into engagement, the potential that protects the busy line establishes an energizing current through the release magnet 11 that flows from the busy 55 contact through the private wiper, through the relay springs 30 and 29, side switch wiper 14, (in second position), private 60 springs 159 and 158 of the private magnet 10, and through the release magnet 11 to the battery lead 114, thence through battery B to ground G. The release magnet then, upon 65 energizing, deprives the switch shaft of its support and also restores the side switch.

to first position, which operation breaks the established energizing circuit for the release magnet, restoring the connector to normal condition.

Suppose that it is desired, for any reason, to call-in on a line that is busy—that is, a line which is protected by a guarding potential. In that event the attendant operates the key f to close the springs 135 and 136 in contact, whereby an energizing circuit is closed through the relay 19 extending from ground G^a through the springs 135 and 136, tip 137 of the plug D', tip spring 138, conductor 139, through the relay 19 to the battery lead 114, thence through battery B to ground G. The said relay, upon energizing, operates to disengage the springs 29 and 30, whereby the private shaft wiper 5 is disconnected from the side switch wiper 14. Now, when the shaft wiper 5 engages a contact point upon which there is a guarding potential, the connector is not given the so-called busy-release, for the protecting potential is not transmitted to the release magnet 11 when the private magnet 10 energizes on the last rotary impulse. Therefore, by means of the connector A the attendant may establish connection with a line when it is protected by a guarding potential. To do so he would take the precaution to throw the key f while he is making a call, so that when the last rotary impulse comes in, the circuit that would ordinarily cause the busy-release of the connector is interrupted at a point between the springs 100 29 and 30 of the relay 19. The aforesaid means for preventing the busy-release, and the means for establishing a metallic circuit from the calling to the called side, around the condensers 16 and 17, are all controlled 105 from the jack C which is under the supervision of the attendant.

It will also be understood, of course, that the connector having these special provisions can be used by the subscribers for establishing ordinary connections, and for such purposes the subscribers use the regular trunk lines leading to the connectors. As illustrated, there are two jacks for each connector thus equipped with means for testing the telephone lines, one jack being connected with the regular or ordinary trunk line leading to such connector, and the other jack being connected with the special or additional trunk line which leads to 110 said connector. The attendant testing a line will, therefore, plug into the jack connected with the regular trunk line leading to the connector, and afterward will also plug into the jack connected with the conductors, such, for example, as the conductors 131 and 139, for the purpose of shunting or short-circuiting the condensers in the connector, as previously explained. It will be understood that my improved testing arrangement 115 120 125 130 135 140 145 150 155 160 165 170 175 180

can be used in systems where the connectors and individual switches and automatic selectors are all located at one and the same central station; for even in such case the attendant can then test the lines without leaving his desk or switchboard. These connectors are not necessarily all at the same station.

The trunking can be arranged on a percentage basis—that is to say, the connectors can be less in number than the total number of subscribers, and the selectors can be employed on the same basis. The subscribers' individual switches will, with such arrangement, be the only switches in the exchange which are the same in number as the subscribers' lines. In an exchange of ten thousand subscribers, divided into groups of one hundred subscribers each, there will then be one testing connector for each group of one hundred lines, and each testing connector can be one of the regular ten connectors allotted to the group of one hundred subscribers. It will be understood, of course, that the connectors are not necessarily ten per cent of the total number of subscribers, as they can be either more or less, according to requirements. As explained, the special or additional apparatus of each testing connector does not in any way interfere with its use by the subscribers for ordinary purposes.

It will be understood, of course, that the conductors X shown in Fig. 1 lead back to an automatic selector, or some other suitable mechanism or apparatus, and that through the medium of these conductors the calling subscriber can control the connector A to seize an idle line. Through the medium of the manual switchboard, however, and the attendant's calling mechanism thereon, said connector can be controlled to seize either a busy or an idle line. The said connector is always controlled over the three-wire trunk comprising the three conductors leading thereto, the third conductor of which is included in the trunk release circuit of the connector. In this way the trunk release circuit may include a contact of the jack, or may include contacts in the selector or other apparatus by which a calling subscriber extends connection to the said connector.

It will be seen that the automatic connectors herein disclosed are of that type in which the line wipers have vertical or straight motion to select groups, and rotary motion to connect with a line in the selected group, the system being of that character in which the subscribers are divided into groups. Each level or horizontal row of line contacts in the connector represents a certain group of subscribers, and after the connector has been operated vertically or in a straight line to select the required level or group, it is then given a rotary motion to

find and connect with a line in the selected group.

What I claim as my invention is:—

1. An automatic telephone exchange system comprising a connector switch, telephone lines terminating at said switch, means by which an attendant may cause said connector switch to seize any one of said lines, condensers in the said connector, and means controlled by the said attendant for shunting or short-circuiting said condensers, whereby a conductively continuous circuit is afforded for testing purposes.

2. An automatic telephone exchange system comprising a connector switch, telephone lines terminating at said switch, means for rendering one or more of said lines busy, means adapted to prevent seizure of a busy line by said connector when the latter is used by a subscriber, mechanism under the control of an attendant for causing said connector switch to seize any one of said telephone lines, and means under the control of the attendant for enabling the connector to seize a busy line.

3. An automatic telephone exchange system comprising telephone lines, means for rendering one or more of said lines busy, an automatic connector, means for preventing seizure of a busy line by a connector when the latter is used by a subscriber, a manual switchboard, and means controllable from the said switchboard for causing the connector to seize a busy line.

4. An automatic telephone exchange system comprising telephone lines, an automatic connector, a trunk line leading to said connector, means by which calling subscribers may use said trunk line for operating said connector to establish connection with a called telephone line, a manual switchboard provided with a jack connected with said trunk line, another jack on said switchboard having direct connection with said connector, means for rendering one or more of said telephone lines busy, means controlled through the medium of said first-mentioned jack for operating said connector, condensers in said connector, and means controlled through the medium of said last-mentioned jack for enabling the connector to seize a busy line, and for shunting or short-circuiting said condensers to afford a conductively continuous circuit for testing purposes.

5. In a telephone system, the combination of telephone lines, an automatic connector, a trunk line leading to said connector, a spring jack connected with said trunk line, a special trunk line leading to said connector, a spring jack for said special trunk line, a calling device and a telephone and means for connecting the same with said first-mentioned jack, and suitable instrumentalities controllable through the medium of said last-mentioned jack for enabling

the connector to seize a busy telephone line and establish a conductively continuous circuit for testing purposes.

6. In a telephone system, the combination of telephone lines, an automatic connector, a pair of voice-current conductors and a special release trunk conductor leading to said connector, a spring jack having contacts connected with said voice-current and release trunk conductors, a pair of conductors leading to said connector for controlling purposes, and a spring jack connected with said last-mentioned pair of conductors, said spring jacks associated together at a point more or less remote from said connector, and cords and plugs for establishing connection with said connector through the medium of said jacks.

7. A trunk line comprising the conductors having one end thereof terminating in a connector and another end terminating in the bank contacts of a selector switch, a jack allotted to said trunk, a plug allotted to said jack, means whereby when the plug is inserted in the jack the said trunk line is made busy, and means in connection with the plug whereby the connector may be operated to establish connection with an automatic line.

8. In a telephone system, a connector, a pair of jacks, a plug for each of said jacks, a calling device and testing apparatus associated with one of said plugs, a rotary back-bridge relay and a vertical back-bridge relay allotted to the connector, means associated with the other of said plugs whereby either the vertical or the rotary back-bridge relays may be energized, and line relays allotted to the connector and adapted to be operated by the said calling device for establishing connection with a called line.

9. In a telephone system, the combination of a connector and a jack, a rotary back-bridge relay, a vertical back-bridge relay and a pair of condensers allotted to the connector, a plug allotted to the jack, means associated with said plug, whereby either the vertical or the rotary back-bridge relays may be operated, the former for opening up the private circuit of the connector, whereby said connector may be put in condition to call on a busy line, and the latter adapted to be energized to short-circuit said condensers.

10. In a telephone system, a connector, a trunk line terminating therein, a jack allotted to said trunk, a plug allotted to said jack, testing means allotted to said plug, a rotary back-bridge relay allotted to said connector, means whereby the connector may be operated to seize or connect with a line, condensers allotted to said connector, one in each side of the talking circuit, and means whereby the said rotary back-bridge relay may be energized to short-circuit said condensers, whereby the seized line may be ex-

tended by metallic circuit to the plug for the purpose of testing.

11. In a telephone system, an automatic connector, telephone lines, means for rendering some of said lines busy, a three-wire trunk leading to said connector, a release circuit including said third wire, and means for manually connecting with said trunk to cause the connector to seize either a busy or an idle line.

12. In a telephone system, telephone lines divided into groups, an automatic connector having one motion to select groups and a second motion to find a line in a selected group, a manual switchboard, and means for controlling said connector from said switchboard by means of its two operating motions to connect with and test either a busy or an idle line.

13. In a telephone system, an automatic connector, telephone lines, means by which a calling subscriber may use said connector for seizing an idle line, a manual switchboard, and means on said switchboard for controlling said connector to cause the latter to seize either a busy or an idle line.

14. A telephone system comprising an automatic connector, telephone lines, means by which a calling subscriber controls said connector to seize an idle line, and means by which an attendant controls said connector to seize either a busy or an idle line.

15. An automatic telephone exchange system in which the subscribers' lines are divided into groups, comprising a connector switch, telephone lines terminating at said switch, means by which an attendant may cause said connector switch to seize any one of said lines, the said connector provided with means having straight motion to select groups and rotary motion to connect with a line in the selected group, condensers in the said connector, and means controlled by the said attendant for shunting or short-circuiting said condensers whereby a conductively continuous circuit is afforded for testing purposes.

16. An automatic telephone exchange system in which the subscribers' lines are divided into groups, comprising a connector switch, telephone lines terminating at said switch, means for rendering one or more of said lines busy, means adapted to prevent seizure of a busy line by said connector when the latter is used by a subscriber, mechanism under the control of an attendant for causing said connector switch to seize any one of said telephone lines, the said connector provided with means having straight motion to select groups and rotary motion to connect with a line in the selected group, and means under the control of the attendant for enabling the connector to seize a busy line.

17. An automatic telephone exchange system in which the subscribers' lines are di-

- vided into groups, comprising telephone lines, means for rendering one or more of said lines busy, an automatic connector, means for preventing seizure of a busy line 5 by a connector when the latter is used by a subscriber, a manual switchboard, and means controllable from the said switchboard for causing the connector to seize a busy line, the said connector provided with means having straight motion to select groups and rotary motion to connect with a line in the selected group.
18. An automatic telephone exchange system in which the subscribers' lines are divided into groups, comprising telephone lines, an automatic connector, a trunk line leading to said connector, means by which calling subscribers may use said trunk line for operating said connector to establish 10 connection with a called telephone line, the said connector provided with means having straight motion to select groups and rotary motion to connect with a line in the selected group, a manual switchboard provided with a jack connected with said trunk line, another jack on said switchboard having direct connection with said connector, means for rendering one or more of said telephone lines busy, means controlled through the 15 medium of said first-mentioned jack for operating said connector, condensers in said connector, and means controlled through the medium of said last-mentioned jack for enabling the connector to seize a busy line, and 20 for shunting or short-circuiting said condensers to afford a conductively continuous circuit for testing purposes.
19. In a telephone system in which the subscribers' lines are divided into groups, 25 the combination of telephone lines, an automatic connector, a trunk line leading to said connector, a spring jack connected with said trunk lines, a special trunk line leading to said connector, a spring jack for said special 30 trunk line, a calling device and a telephone and means for connecting the same with said first-mentioned jack, and suitable instrumentalities controllable through the medium 35 of said last-mentioned jack for enabling the connector to seize a busy telephone line and establish a conductively continuous circuit 40 for testing purposes, the said connector provided with means having straight motion to select groups and rotary motion to connect 45 with a line in the selected group.
20. In a telephone system in which the subscribers' lines are divided into groups, the combination of telephone lines, an automatic connector, a pair of voice-current conductors and a special release trunk conductor leading to said connector, the said connector provided with means having straight motion to select groups and rotary motion to connect with a line in the selected group, 55 a spring jack having contacts connected with
- said voice-current and release trunk conductors, a pair of conductors leading to said connector for controlling purposes, and a spring jack connected with said last-mentioned pair of conductors, said spring jacks associated together at a point remote from said connector, and cords and plugs for establishing connection with said connector through the medium of said jacks.
21. In a telephone system in which the subscribers' lines are divided into groups, a trunk line comprising the conductors having one end thereof terminating in a connector and another end terminating in the bank contacts of a selector switch, the said connector provided with means having straight motion to select groups and rotary motion to connect with a line in the selected group, a jack allotted to said trunk, a plug allotted to said jack, means whereby when the plug 85 is inserted in the jack the said trunk line is made busy, and means in connection with the plug whereby the connector may be operated to establish connection with an automatic line.
22. In a telephone system in which the subscribers' lines are divided into groups, a connector, a pair of jacks, a plug for each of said jacks, a calling device and testing apparatus associated with one of said plugs, a rotary back-bridge relay and a vertical back-bridge relay allotted to the connector, means associated with the other of said plugs whereby either the vertical or the rotary back-bridge relays may be energized, and 90 line relays allotted to the connector and adapted to be operated by the said calling device for establishing connection with a called line, the said connector provided with means having straight motion to select 95 groups and rotary motion to connect with a line in the selected group.
23. In a telephone system in which the subscribers' lines are divided into groups, the combination of a connector and a jack, the said connector provided with means having straight motion to select groups and rotary motion to connect with a line in the selected group, a private circuit, a pair of condensers, a rotary back-bridge relay, and 100 a vertical back-bridge relay allotted to the connector, a plug allotted to the jack, means associated with said plug, whereby either the vertical or rotary back-bridge relays may be operated, the former for opening up the 105 private circuit of the connector, whereby said connector may be put in condition to call on a busy line, and the latter adapted to be energized to short-circuit said condensers.
24. In a telephone system in which the subscribers' lines are divided into groups, a connector, a trunk line terminating therein, a jack allotted to said trunk, a plug allotted to said jack, testing means allotted to said 110
- 125
- 130

plug, a rotary back-bridge relay allotted to said connector, means whereby the connector may be operated to seize or connect with a line, the said connector provided with 5 means having straight motion to select groups and rotary motion to connect with a line in the selected group, condensers allotted to said connector, one in each side of the talking circuit, and means whereby the 10 said rotary back-bridge relay may be energized to short-circuit said condensers, whereby the seized line may be extended by metallic circuit to the plug for the purpose of testing.

15 25. In a telephone system in which the subscribers' lines are divided into groups, an automatic connector, the said connector provided with means having straight motion to select groups and rotary motion to 20 connect with a line in the selected group, telephone lines, means for rendering some of said lines busy, a three-wire trunk leading to said connector, and means for manually connecting with said trunk to cause the 25 connector to seize either a busy or an idle line.

26. In a telephone system, subscribers' lines divided into groups, an automatic connector, the said connector provided with 30 means having straight motion to select groups and rotary motion to connect with a line in the selected group, a manual switchboard, and means for controlling said connector from said switchboard to connect 35 with either a busy or an idle line.

27. In a telephone system, subscribers' lines divided into groups, an automatic connector, the said connector provided with means having straight motion to select 40 groups and rotary motion to connect with a line in the selected group, means by which a calling subscriber may use said connector for seizing an idle line, a manual switchboard, and means on said switchboard for 45 controlling said connector to cause the latter to seize either a busy or an idle line.

28. A telephone system in which the subscribers' lines are divided into groups, comprising an automatic connector; the said connector provided with means having straight 50 motion to select groups and rotary motion to connect with a line in the selected group, telephone lines, means by which a calling subscriber controls said connector to seize an idle line, and means by which an attendant controls said connector to seize either a 55 busy or an idle line.

29. In a telephone system, an automatic connector, telephone lines divided into groups, means for rendering some of said 60 lines busy, a three-wire trunk leading to said connector, and means for manually connecting with said trunk to cause the connector to seize either a busy or an idle line, said connector having vertical motion to select groups and rotary motion to find the 65 called line in any selected group.

30. In a telephone system, an automatic connector, telephone lines divided into groups, a manual switchboard, and means 70 for controlling said connector from said switchboard to connect with either a busy or an idle line, said connector having one motion to select groups and a second motion to find the called line in any selected group. 75

31. In a telephone system, subscribers' lines divided into groups, an automatic testing apparatus comprising a plug and jack and connector, and means operative through the plug and jack for connecting the connector with either a busy or an idle telephone line, said connector having vertical motion to select groups and rotary motion to find the called line in any selected group, substantially as shown and described. 80 85

Signed by me at Chicago, Cook county, Illinois, this 26th day of March, 1907.

WILSON L. CAMPBELL.
